COMBINED SLIDE RULE AND PENCIL

Marvin H. Oleson, Adelphi, Md.

Application November 20, 1953, Serial No. 393,345

8 Claims. (Cl. 235—70)

This invention relates to improvements in slide rules and more particularly to a novel slide rule construction well adapted for association with a mechanical pencil, although not restricted to such association.

The rule includes an elongated body having a longitudinal groove, and an elongated slide in said groove, said body and slide having cooperable calculating graduations; and one object of the invention is to make novel provision for normally holding said slide against movement with respect to said body.

Another object of the invention is to provide the slide holding means in the form of a split collar seated in a peripheral groove in the body and movable into and from a transverse groove in the slide, whereby this slide may be held against movement or freed for movement, as required.

A further object of the invention is to provide a resilient split collar for the aforesaid purpose, said collar being held in its operative position under the influence of its own resiliency.

A still further object of the invention is to provide a novel construction in which the split collar may be readily expanded to released position by thumb pressure on its ends.

Another object of the invention is to provide a novel construction in which the split collar, when released, constitutes a slidable indicator cooperable with the graduations of the body and slide.

Yet another object of the invention is to provide a slide rule of the general type set forth, in which a split collar constituting a slidable indicator, is held against rotation by means of lugs on the collar ends slidably engaged with longitudinal grooves in the body.

A further object is to provide walls of the last named grooves with notches which normally receive the lugs of the collar ends and hold the collar against sliding, the lugs however being movable from the notches by thumb pressure on said collar ends, thereby freeing the collar for sliding movement.

A still further object is to provide a novel construction in which a split collar which normally holds the slide against movement, is manually turnable upon the body to and from operative position.

Yet another object is to provide an unusually simple and inexpensive construction which may be easily constructed from a modern plastic, thus facilitating manufacture and permitting profitable sale of the article at a reasonable price.

With the above and other objects in view that will become apparent as the nature of the invention is better understood, the same consists in the novel form, combination and arrangement of parts hereinafter more fully described, shown in the accompanying drawing, and particularly claimed.

In the drawing:

Fig. 1 is a front elevation of the preferred form of construction;

Fig. 2 is a rear elevation;

Fig. 3 is an enlarged transverse sectional view on line 3—3 of Fig. 2, showing the split collar in its normal position holding the slide against movement;

Fig. 4 is a view similar to Fig. 3 but showing the split collar released;

Fig. 5 is an enlarged transverse sectional view on line 5—5 of Fig. 2.

2

Fig. 6 is an enlarged fragmentary rear elevation of a portion of the body;

Fig. 7 is a fragmentary front elevation showing a modified construction;

Fig. 8 is an enlarged transverse section on line 8—8 of Fig. 7;

Fig. 9 is a fragmentary rear elevation of the modified construction shown in Fig. 7;

Fig. 10 is an enlarged transverse sectional view on line 10—10 of Fig. 9, and

Fig. 11 is a fragmentary side elevational view of the slide shown in Fig. 1.

Structural preferences have been disclosed in the drawing and will be rather specifically described, but it is to be understood that variations may well be made.

In the form of construction shown in Figs. 1 to 6, the elongated body 12 of the improved slide rule is also the body of a mechanical pencil, the pencil lead 13 being adjustable by turning the tip 14 with respect to said body. However, it is not essential that the invention be associated with a pencil or the like as it operates totally independently thereof.

A longitudinal groove 15 is formed in the front side of the body 12, and an elongated slide 16 is slidably mounted in said groove 15. The side walls of the groove 15 are undercut and the side edges of the slide are shaped in conformity with said side walls to prevent lateral movement of the slide from the groove.

The body 12 and slide 16 have cooperating graduations 17 and 18 respectively. The character of these graduations may be varied according to the character of calculations it is desired to make with the rule, that is, said graduations may be of a character to permit multiplication and division, or said graduations may be of such a

nature as to permit any other calculations to be made which are commonly made by means of a calculating rule.

In the rear side of the body 12, there are two circumferentially spaced longitudinal grooves 19. The inner walls of these two grooves have notches 20 near the upper end of the body 12. Two shallow circumferentially extending grooves 21 are also formed in the body 12 near the upper end of the latter. One of the grooves 21 extends from the front groove 15 substantially to one of the rear grooves 19. The other of the grooves 21 extends from the front groove 15 substantially to the other of the rear grooves 19. The grooves 21 diminish gradually in depth toward the rear grooves 19, and their depth at said grooves 19 is nil.

The upper end portion of the slide 16 has a transverse groove 22 which registers with the grooves 21 when said slide is in the fully retracted position shown in the drawing.

A transversely split resilient collar 23 is seated in the grooves 21 and normally engages the groove 22 of the slide 16 as shown in Fig. 3, to hold said slide 16 against movement. The ends of the collar 23 have lugs 24 which are normally seated in the notches 20 of the rear groove 19, as seen in Fig. 3. These lugs 24 are thus normally out of alignment with the grooves 19 but are of such width as to be receivable in said grooves 19 when the ends of the collars are spread farther apart, as seen in Fig. 4. Such spreading of the collar ends so increases the diameter of the collar 23 as to move this collar from the groove 21 of the body 12 and from the groove 13 of the slide 16. Thus, the slide 16 is freed for longitudinal movement and the collar 23 is also freed for movement along the body and slide. The collar 23 then acts as a cursor or indicator cooperable with the graduations 17 and 18.

If the collar 23 be of transparent plastic, as preferred, it may have an indicating line 25 cooperable with the graduations 17 and 18.

To effect the necessary spreading of the ends of the collar 23, it is simply necessary to press said ends toward the center of the body 12 with one thumb, as seen in Fig. 4, whereupon the end portions of the collar slide in opposite directions around the body, causing the required expansion of the collar to clear the grooves 21 and 22. When the parts are returned to their normal positions after performing a desired calculation, the collar

23 again snaps into the grooves 21 and 22, and the lugs 24 again enter the notches 20. The collar 23 and slide 16 are thus held against accidental movement, and the lugs 24 and notches 20 prevent accidental displacement of the collar ends.

In the modified construction shown in Figs. 7 to 10, the front of the body 12^a is grooved at 15^a to receive the slide 16^a, and the rear of said body has grooves 19^a corresponding to the grooves 17 but provided with no notches such as 20. The body 12^a has a shallow circumferential groove 21^a intersecting the groove 15^a, and the slide 16^a has a shallow groove 22^a which aligns with said groove 21^a when said slide is fully retracted.

A transversely split resilient collar 23^a is seated in the groove 21^a and normally extends into the groove 22^a to hold the slide 16^a against movement. However, this collar 23^a may be turned by hand to a position in which it will free the slide 16^a, as shown in Fig. 7. The resiliency of the collar 23^a causes it to frictionally grip the body 12^a and remain in any position to which it may be turned.

A cursor or indicator collar 26 is slidable frictionally on the body 12^a and has lugs 27 at its ends slidable in the grooves 19^a, preventing it from accidentally turning out of cooperative relation with the body and slide graduations.

From the foregoing, it is believed that the construction and use of the invention will at once be apparent, and while there are herein shown and described the preferred embodiments of the invention, it is nevertheless to be understood that minor changes may be made therein without departing from the spirit and scope of the invention as claimed.

I claim:

1. In a slide rule, an elongated cylindrical body having a longitudinal groove, an elongated slide extending longitudinally in said groove, said slide having a transverse groove in its outer side near one of its ends, and a split collar surrounding said body and movable into and out of said groove of said slide to either hold the latter or free it for use, said body having a peripheral groove receiving said split collar.

2. In a slide rule, an elongated body having a longitudinal groove, an elongated slide extending longitudinally in said groove, said body and slide having cooperating graduations, and a split indicator collar jointly surrounding said body and slide and cooperable with said graduations, the ends of said collar having lugs projecting beyond the inner periphery of said collar, said body having parallel longitudinal grooves slidably receiving said lugs.

3. A structure as specified in claim 1; said body and slide having cooperating graduations, said split collar being resilient and being expandable from said peripheral

groove of said body and said transverse groove of said slide, whereby said collar also forms an indicator slidable with respect to said body and slide.

4. A structure as specified in claim 1; said collar being rotatable from the groove of said slide to free said slide for operation.

5. In a slide rule, an elongated body having a longitudinal groove, an elongated slide extending longitudinally in said groove, said body and slide having cooperating graduations, and a split indicator collar jointly surrounding said body and slide and cooperable with said graduations, said slide and body having portions normally engaged by said collar to hold said body, slide and collar against relative sliding, said collar being resilient and being normally expansible from said portions of said body and slide to free said body, slide and collar for relative longitudinal movements.

6. In a slide rule, an elongated body having a longitudinal groove, an elongated slide extending longitudinally in said groove, said body and slide having cooperating graduations, said body having two shallow arcuate grooves extending circumferentially of said body from opposite sides of said longitudinal groove, said shallow grooves gradually decreasing in depth away from said longitudinal groove and having nil depth at the ends thereof remote from said longitudinal groove, said slide having a transverse groove to normally register with said arcuate grooves, and a split resilient collar normally seated in said arcuate and transverse grooves to hold said slide against movement, the ends of said collar being disposed at the nil-depth ends of said arcuate grooves, whereby said collar may be manually expanded from said arcuate and transverse grooves to free said slide and to allow movement of said collar longitudinally of said body and slide.

7. A structure as specified in claim 6; said ends of said collar having lugs projecting beyond the inner periphery of said collar, said body having parallel longitudinal grooves in which said lugs are slidably when said collar is expanded, the inner side walls of said parallel grooves having notches in which said lugs are normally seated.

8. In a slide rule, an elongated cylindrical body having a longitudinal groove, an elongated slide extending longitudinally in said groove, said body and slide having cooperating graduations, a split collar rotatably embracing said body and slide and held against longitudinal movement on said body, said slide having a groove into which said collar is rotatable to normally hold said slide against movement, and an indicator collar surrounding said body and cooperable with said graduations.
